UNITED STATES PATENT OFFICE.

CHARLES J. MACKEREY, OF PHILADELPHIA, PENNSYLVANIA.

STEAM-TRAP.

1,118,300.

Specification of Letters Patent.

Patented Nov. 24, 1914.

Application filed February 28, 1914. Serial No. 821,670.

To all whom it may concern:

Be it known that I, CHARLES J. MACKEREY, a citizen of the United States, residing at United States ship *Illinois*, Navy Yard, Philadelphia, in the county of Philadelphia and State of Pennsylvania, have invented certain new and useful Improvements in Steam-Traps, of which the following is a specification.

10 This invention relates to steam traps, and more particularly to steam traps designed for use on moving bodies, such as boats, for collecting condensed steam in a steam circulatory system from whence it may be re-introduced into the boiler.

One object of the present invention is to provide a simple and practical steam trap which will be cheap to manufacture and install.

20 Another object is to provide a steam trap that will be highly efficient in operation and not likely to get out of order under unusual conditions.

A further object is to provide a steam trap which will permit of convenient manipulation, adjustment and assembling of parts.

Other objects will be in part obvious and in part hereinafter pointed out.

30 The present invention accordingly consists in the features of construction, combination of elements and arrangements of parts which will be exemplified in the device hereinafter described, and the scope of 35 the application of which will be indicated in the following claims.

In the accompanying drawing, wherein is illustrated one of various possible embodiments of the present invention, Figure 1 is a 40 longitudinal section of the complete device; Fig. 2 is a detail view partly in section of the valve and valve chamber; Fig. 3 is a detail sectional plan view taken on line 2—2, Fig. 2, of a portion of the valve actuating mechanism.

45 Similar reference characters denote corresponding parts in the figures.

Referring now to the drawings in detail, 50 6 denotes a collecting tank located in any convenient part of the circulatory system, provided at the top with a valved inlet 5 through which the steam and condensed vapor may enter, and at the side with an outlet 7. Between the inlet and outlet is a valve and valve controlling mechanism

adapted to permit the proper discharge of condensed steam under varying conditions.

The valve mechanism is located in a chamber secured to one side of the tank 6, and is provided with a sealed cover 9 which may be removed at will for replacing parts of the valve if required. A valve seat 11 is located in the top of the outlet 7 and co-acts with a reciprocating valve 10, the stem 12 of which passes through a threaded plug 13. The upper part of the stem is threaded and carries a lower collar 15 and an upper collar 14, adjustable as desired to regulate the time of actuation, while the top is provided with a head 16 engaged by the forked end 17 of the part 18 of the valve stem. This part 18 passes through stuffing box 19 and is provided with an actuating hand wheel 20. Thus by turning this wheel 20 the valve may be held in either open or closed position, or when in its intermediate position an automatic operation of the device is permitted as will be hereinafter described. A scale 21 is provided on or adjacent the part 18 in order that its position may be determined on inspection.

70 The valve actuating mechanism, a part of which is shown in Fig. 3, comprises a bucket 22 carried at one end of a lever mechanism pivoted in a hollow casting 23 secured to the side wall of the tank and provided with a forked end 24 passing through an opening 25 into the valve chamber and engaging the valve stem 12 between the collars 14 and 15. This lever mechanism is made of hollow piping, the fulcrum 26 having an opening 27 communicating with the hollow casting 23. Two pipes 28 connect the fulcrum with the ends of a T member 29, which in turn is connected with a siphon pipe 30, dipping down into the bucket. By having two pipes 28 connected in this manner there is less chance of binding at the fulcrum for example if the device is in use on a boat where rolling prevents the device from always occupying a normal position.

100 Communication is thus established from the bottom of the bucket 22 through the pipe 30, T-member 29, arms 28, fulcrum 26, hollow casting 23, thence through the opening 25 to the valve chamber. The water or liquid will then pass through holes 31 in the pipe 7 and out therethrough when the valve is open as shown in Fig. 2.

110 The operation of this device is substan-

tially as follows: The condensed steam or vapor entering through the inlet 5 will gradually fill the tank and cause the bucket to rise, and the forked end 24 will bear down 5 on the collar 14 and hold the valve 11 closed. When further upward movement of the bucket is prevented by engaging the top of the tank for example the water will flow over the top and fill the bucket, thus causing 10 it to sink. The forked end 24 will then contact with the upper collar 15 and raise the valve 11 and the steam pressure will force the water out of the tank through the pipes and hollow connections as above described. 15 As long as the pipes are filled with water there can be no material escape of steam, and as soon as the bucket is substantially empty it will rise to the surface of the remaining water in the tank and automatically 20 shut off the valve until the tank is again filled. By turning the valve wheel 20 the valve may be permanently closed as when making repairs, or permanently open as when blowing out the connections with 25 steam. It will also be noted that the present construction permits of ready removal of the valve parts. The side of the tank 6 to which the mechanism is secured may be easily removed by loosening the connecting bolts 32 30 and the parts of the casting 23 may be separated by removal of bolts 3. In a similar manner the cover 9 may be removed and by loosening the plug 13 the valve and valve stem may be drawn out and replaced as desired.

It is thus seen the invention provides a simple and practical device adapted to accomplish among others all of the objects and advantages above set forth.

40 As many changes could be made in the above construction and many apparently widely different embodiments of my invention could be made, without departing from the scope thereof, I intend that all matter 45 contained in the above description or shown in the accompanying drawing shall be interpreted as illustrative and not in a limiting sense.

Having thus described my invention what

I claim as new and desire to secure by Letters Patent is:

1. In a steam trap mechanism, in combination, a tank having an inlet, a separate valve chamber having an outlet, a valve in said chamber, means within the tank operative through the dividing partition for actuating said valve said actuating mechanism including a float adapted to fill with liquid when the tank is substantially full and a pair of pipes leading from the upper part of 55 said tank adapted to prevent lateral movement thereof, said valve chamber having a removable side to permit access to and removal of the valve mechanism.

2. In a steam trap mechanism, in combination, a closed receptacle having an inlet, a separate valve chamber adjacent said receptacle, having an outlet therefrom, a valve in said chamber, valve actuating mechanism comprising a pair of pipes fulcrumed in the 60 dividing wall between the receptacle and valve chamber carrying a second receptacle at one end with which they have a siphon connection and adapted to actuate the valve at the opposite end, the opposite ends of 70 said device being rigidly secured, thereby preventing lateral movement of said valve actuating mechanism.

3. In a steam trap mechanism, in combination, a receptacle having an inlet, a valve 80 chamber having an outlet formed of an open ended pipe, a valve in the open end of said pipe, means for reciprocating the valve to open and close the pipe, manually operated means outside of said chamber having lost 85 motion connection with said valve, a cover for said valve chamber permitting access to the valve, said parts being positioned and arranged to permit removal of the valve from said open ended pipe without disturbing the means for manually operating said valve.

In testimony whereof I affix my signature in presence of two witnesses.

CHARLES J. MACKEREY.
